UNITED STATES PATENT OFFICE.

HOWARD EMERSON AMES, OF WASHINGTON, DISTRICT OF COLUMBIA.

SANITARY RECEPTACLE.

1,344,531.

Specification of Letters Patent. Patented June 22, 1920.

Application filed September 25, 1918. Serial No. 255,686.

To all whom it may concern:

Be it known that I, HOWARD E. AMES, a citizen of the United States, residing at Washington, in the District of Columbia, have invented certain new and useful Improvements in Sanitary Receptacles; and I do hereby declare the following to be a full, clear, and exact description of the invention, such as will enable others skilled in the art to which it appertains to make and use the same.

My invention relates to sanitary vessels intended for use in hospitals, sanitariums, trenches, or other places where it is desired to keep garbage or other similar material protected in a vessel which automatically closes and is protected from flies, and is also protected from the invasion of animals, such as cats, rats, dogs or the like, and which keeps out rain or snow, when used out of doors.

In the trenches particularly, it is found that the garbage or other like material attracts flies innumerable tending to spread contagion, and the sun's rays cause the same to putrefy and create offensive odors; and it is the object of my invention to provide a receptacle or plurality of receptacles, in which all such material can be kept in a closed and sealed condition, except when it is desired to temporarily open the receptacle to empty the same.

My invention is also intended to provide a receptacle, in which solid and liquid matter may be kept separate, such, for instance, as vegetable parings, corn husks, bones, or the like in one compartment, and slops or the like in the other.

My invention is also intended to provide a knock-down receptacle, the various parts of which may be standardized, and in which the main receptacle and also the inclosed receptacles may be nested for shipment, like strawberry boxes, and in which the tops and other parts may be stored in the upper receptacle of the nest. Furthermore, by standardizing the parts it will not be necessary to have each part fit each individual receptacle, and injured or missing parts may be quickly supplied. Moreover, if one of the receptacles, or any of its component parts, is damaged, the entire receptacle or the various component parts thereof may be readily replaced from the standard stock on hand.

My invention also consists in arranging the parts so that they may be quickly as-

sembled, or dis-assembled for purposes of transportation and shipment.

My invention will be more fully understood after reference to the accompanying drawings, in which like parts are indicated by similar reference symbols throughout the several views, and in which:—

Figure 1 represents a plan view of the complete receptacle, with the top in the closed position.

Fig. 2 is a side elevation of the complete receptacle shown in Fig. 1, showing the top in the closed position, and illustrating the means for automatically lifting the top incident to the operation of raising the bail.

Fig. 3 is a similar view of Fig. 2, but shows the top lifted and the receptacle in the open position.

Fig. 4 shows a central vertical section through the receptacle along the line 4—4 of Fig. 1, parts being shown in elevation.

Fig. 5 is a detail showing the detachable seat.

Fig. 6 shows one of the detachable loops used in assembling the parts; and

Fig. 7 shows one of the detachable U-bolts used in assembling the parts.

A represents the main receptacle, having the front wall A' inclined forward for convenience in emptying the same, and having the rear walls A², the side walls A³ and A⁴ and the bottom A⁵.

The upper edges of the various sides of the receptacle are beaded, and a reinforcing wire a is inserted, as shown in Fig. 4, and the front wall A' of the receptacle A is cut away somewhat, as at a°, see Fig. 4, so that the contents may be more conveniently poured out; this cut-away portion being closed by the overhanging edge of the cover, as will be hereinafter described.

The reinforcing rod a' at each upper edge of each side of the receptacle is looped, as at a², to form a hinge bearing for the cover, see Figs. 2 and 3; and a handle A° is connected to the back of the receptacle for convenience in emptying the same. This handle A° is preferably detachably connected to the receptacle by U-shaped loops a³, shown in detail in Fig. 6, the U portions of said loops being projected through slots cut in the side of the receptacle and engaging the ends of the handle. These ends may be sprung out of the loops and the loops removed, and vice versa.

B represents the bail, which is preferably made of a continuous length of wire twisted

as shown, and having loops pivoted on the trunnions c projecting from the sides of the receptacle. These trunnions are preferably formed of a single length of bent wire C , 5 having the projecting end c passing through a hole in the side of the receptacle, and having the curved end c' passing through similar holes in the side of the receptacle, as shown in Figs. 3 and 4. The outwardly projecting end c is provided with a pivoted locking piece c^2 which when turned on end 10 may be passed through the hole in the receptacle and through the eye in the bail B , but which will lock said bail against slipping off the trunnion when said piece c^2 is turned to the position shown in Figs. 1 to 3.

At one side of the receptacle the bail is provided with a curved arm b , projecting beyond the trunnions as shown in Figs. 2 20 and 3, which arm operates the mechanism for lifting the hinged cover, as will be hereinafter described.

The top of the receptacle is closed mainly by the hinged cover E , but partly by the 25 plate D , which slides on the rear upper portion of the receptacle from the rear, and is locked in place by the transverse rods L and M^2 to be hereinafter described.

The hinged cover E is provided with a 30 downwardly projecting flange e , adapted to close the opening a^o at the upper edge of the front face of the receptacle, as shown in Figs. 2 and 4, and the sides of this cover fit snugly along the top of the sides A^3 and 35 A^4 of the receptacle. The front edge of the cover is provided with a reinforcing wire G , secured thereto in any convenient way, preferably by means of detachable U-bolts g' and nuts, as shown in Fig. 7, and the ends 40 of this wire are bent over as at g to engage the bail should the attempt be made to lift the cover without lifting the bail. This renders it impossible to lift the cover without first swinging up the bail, and will thus 45 prevent cats, or other animals, from lifting up the cover in order to secure access to the contents of the receptacle.

The cover is provided with a hinged rod or wire H' , which is preferably V-shaped, 50 to form a stiffening rib for the top of the cover, and is bent as at h' and h^2 to form trunnions for the cover. One of these trunnions h^2 is provided with a projecting arm h^3 , pivotally connected to the operating bar 55 I , as will be hereinafter described.

This rod H' is held in place by a plate H which is secured to the cover E by means of the screw h^o and the U-bolts f' , which latter engage the cross rod F looped as at 60 f^o to pass over the part h' of the rod H' , and having the projecting ends f , which ends serve as stops for the bail B .

The position of these stops may be adjusted to give more tilt to the lid by reversing 65 the U-bolts f' , thus fixing the cross rod

F and the stops f farther back on the top of the main receptacle, which will permit the lid E to swing through a greater angle rearward.

I represents the operating bar, which is 70 preferably also of bent wire, having its rear end i bent outward to engage the crank arm h^3 and held against accidental displacement by means of the pivoted locking piece i^o . This operating bar or wire is provided with 75 a loop i' and with a straight arm i^2 , which engages in the loop i^o projecting from the side of the receptacle A , as shown most clearly in Fig. 2.

K represents a link which is also prefer- 80 ably made of bent wire, having the outwardly projecting arms k and k' , and the bent central portion k^2 , which bent central portion projects downward, as at k^3 , see Fig. 2. This bent central portion has a double 85 function, in that it serves to hold the link K flat up against the face of the receptacle, without any tendency of the link to become twisted, and the downwardly projecting portion k^3 serves as a stop to engage the arm 90 i^2 of the operating rod I , and thus to prevent the arm k' of the link from falling out of the path of the curved arm b projecting from the bail B , as shown in Figs. 2 and 3. This link has the outwardly projecting arm 95 k engaging in the loop i' of the bar I , and the other outwardly projecting arm k' lies in the path of the travel of the curved arm b projecting from the bail B .

L represents a tie bolt or rod which serves 100 the double function of locking the sliding piece D in place, and also supporting the rear end of the seat piece M , as will be hereinafter described. This bar L is preferably provided with a hinged lock l similar to the 105 hinged lock i^o already described in connection with the operating bar I .

The seat piece M (see Figs. 1 and 5), consists of two curved plates M' secured on the curved rod M^2 , which rod is substantially 110 U-shaped and has arms m terminating in front supports m' of the seat piece, which front supports rest on the sides of the main receptacle A . The two plates M' slope slightly inward, and the outer sides m^3 115 of these plates are curved to fit snugly over the sides of the main receptacle, and these plates preferably terminate in the curved lugs m^4 , all as shown most clearly in Fig. 5.

The arms m of the rod M^2 rest on the 120 cross rod L , as shown in Fig. 4, and thus a strong support for the rear end of the seat piece is provided.

The front end of the seat piece is supported on the side walls of the main receptacle A . To prevent the piling up of solid matter in the receptacle, I provide a stirring device, consisting preferably of a single wire member N , having a loop n and bent portion n' terminating in the handle n^2 , 130

projecting above the top of the receptacle and with a downwardly projecting arm n^3 engaging in the U-bolt n^o , which is in construction similar to the U-bolt g' shown in Fig. 7.

- This leveling device may be operated from the outside of the vessel entirely clear of the top. In order to separate the solid materials, such as vegetable parings, or the like, 10 from the liquid materials, such as slops, or the like, I provide a separate receptacle P for the liquid material, adapted to fit snugly into the forward end of the main receptacle, and to be removed therefrom by 15 means of the bail p , and emptied separately before the main receptacle is emptied.

In order to protect as far as practicable the inner walls of the main receptacle from soiling or corrosion by the contents thrown 20 into the same, I preferably provide a coating of paper X , (see Fig. 4), such as a paper bag, or a paper lining, or the like, and which, when the receptacle is emptied, will fall out together with the contents of 25 the same, leaving the bottom and walls of the receptacle protected by such paper lining fairly clean.

The operation of the device is as follows:—

- 30 When used as a garbage can the bucket P can be removed and the leveling device N may either be allowed to remain in place or be removed as it then has no special utility.
- 35 If the device is to be used as a commode, for which it is primarily intended, the bucket P and leveling device N should both be in place. By moving the bail B from the 40 position shown in Figs. 1, 2 and 4, to the position shown in Fig. 3, the arm b of the bail will be caused to engage the arm b' of the link K , and the operating bar I will be moved from the position shown in Fig. 2 to that shown in Fig. 3, which will swing the 45 lid E to the open position shown in Fig. 3, in which position, beyond the perpendicular it will remain until the bail B is swung in the reverse direction for swinging down the lid E .
- 50 When the lid is raised the soldier, or patient, seats himself on the plates M' of the seat piece M , and the fecal matter will fall into the main receptacle in rear of the bucket P , while the urine drawn during the 55 stool will fall into the bucket P , and is thus kept separate from the fecal matter.
- As the fecal matter piles up or pyramids in the receptacle, its crest may be broken off or leveled by turning of the leveling device N , when the loop n will remove the top 60 of the mass, and thus the commode may be used by a large number of persons without danger of any one being soiled in any way.
- By having the front wall of the receptacle 65 cut away as at a^o , and making the receptacle

low so that the users have to bend their knees upward when at stool, danger of soiling the legs or clothing of the user from contact with the front wall of the receptacle is avoided.

The handle of the bucket P being swung forward as shown in Fig. 4 is also unlikely to be soiled by the users of the device.

It will be noted that the lid is lifted by lifting the bail, and that the leveling device 75 is operated from the exterior of the receptacle, so that there is no necessity for any one of the users of the device to become soiled in any way.

I have estimated that a receptacle of convenient size, used as a trench commode, will supply the needs of about fifty men if emptied once only in twenty-four hours. It may be used in the trenches during the day time and safely emptied at night.

In order to empty the same, lift the lid, remove the bucket P and pour out its contents, and then dump out the more solid contents of the receptacle. By having the fecal matter and the urine separated, both 90 may be readily removed from the receptacle, and the formation of a gluey, sticky, offensive mass, such as will occur when the two are mixed, will be avoided.

The paper bag or lining used in the fecal 95 compartment, will enable the fecal matter to be poured out without adhering to the inner sides of the receptacle.

While the device is specially adapted for use in the trenches or in military encampments, or in hospitals, it is also adapted for use on farms or at other places where there is no suitable sewerage system; or where it is desired to preserve the excreta for use as a fertilizer.

The device may be used in such places with or without a suitable disinfectant for several days and then carried away and emptied.

It has been found in practice that in the 110 use of the device either by men or women, a similar separation of the urine from the fecal matter will result, owing to the location of the urine bucket in front of the fecal chamber and in front of and below the 115 seat.

It will thus be seen that I provide a portable device of convenient size which may be used either as a garbage can or as a commode; and which, when used as a commode, permits the separation of the urine from the fecal matter, and the ready dumping out of both; also which may be used consecutively by a large number of persons without danger of soiling any one of the 120 users.

For convenience in shipment I purposely construct the device so that the various parts may be knocked down and put together again, and so that a number of the 130

main receptacles and also of the inclosed buckets may be nested.

To knock-down the apparatus, suppose it to be set up complete as shown in Figs. 1 to 4, remove the rod L and slide back the rear section of the top and detach the lifter therefrom, now remove the lid by unscrewing the screws h^o and U-bolts f' , remove the triangular top piece H, spring out the bent rod H' and then remove the lid. The rod G may be left in place on the lid, or removed after disengagement with the U-bolts g' .

Now, remove the seat piece and remove the bucket P, remove the handle with its pivot, also the link K, and the sliding rod I, remove the various fastening devices, then remove the handle A^o , and the entire main receptacle will be free from protuberances, and a series of same may be nested together. It will be obvious also that a series of buckets P may be nested together.

To assemble the parts, insert the back piece D of the top, put in the rod L, spring in the leveling device, put on the seat piece, put in the lid lifter, put on the lid, fasten the plate H over the lid lifter and lid, insert the link K in the operating rod, insert the operating rod in its guide and connect the operating rod to the crank h^o and put the handle pivot and handle in place and insert the bucket P. The parts will then be in the assembled position as indicated in Fig. 4.

It will be noted that when the apparatus is set up for any of its various uses, the lid is securely connected to the receptacle and cannot be removed without disassembling the entire device. This will prevent the accidental loss of the cover, with the consequent ineffectiveness of the apparatus, and will also save the additional trouble of having to lift the cover from the ground, or to find it when it is mislaid; the cover being always firmly attached to the receptacle when it is in use.

I have shown the various operating, lifting and reinforcing rods made of round wire, this for convenience in manufacture; but flat bars might obviously be substituted in a number of places for the round wire.

It will also be obvious that various other modifications might be made in the apparatus, and in the construction, combination and arrangement of parts which could be used without departing from the spirit of my invention; and I do not mean to limit the invention to such details except as particularly pointed out in the claims.

Having thus described my invention, what I claim and desire to secure by Letters Patent of the United States is:—

1. A device of the character described, comprising a receptacle, a hinged lid for same, a bail and means automatically op-

erated by the lifting of said bail for lifting said lid, a seat piece detachably mounted on the top and rear of said receptacle, and covered by said lid when closed, and a bucket detachably mounted in said receptacle in front of said seat, substantially as described. 70

2. A device of the character described, comprising a receptacle, a hinged lid for same, a bail and means automatically operated by the lifting of said bail for lifting said lid, lugs carried by said lid and normally engaging said bail and preventing the lifting of said lid independently of said bail, a seat piece detachably mounted on the top and rear of said receptacle, and covered by said lid when closed, and a bucket detachably mounted in said receptacle in front of said seat, substantially as described. 75

3. A device of the character described, comprising a receptacle cut away on its front upper edge, a hinged lid for same having a downwardly projecting flange registering with said cut away portion of the receptacle, a bail and means automatically operated by the lifting of said bail for lifting said lid, a seat piece detachably mounted on the top and rear of said receptacle, and covered by said lid when closed, and a bucket detachably mounted in said receptacle in front of said seat, substantially as described. 85 90 95

4. A device of the character described, comprising a receptacle cut away on its front upper edge, a hinged lid for same having a downwardly projecting flange registering with said cut away portion of the receptacle, a bail and means automatically operated by the lifting of said bail for lifting said lid, lugs carried by said lid and normally engaging said bail and preventing the lifting of said lid independently of said bail, a seat piece detachably mounted on the top and rear of said receptacle, and covered by said lid when closed, and a bucket detachably mounted in said receptacle in front of said seat, substantially as described. 100 105 110

5. A device of the character described, comprising a receptacle, a hinged lid for same, a bail and means automatically operated by the lifting of said bail for lifting said lid, a seat piece detachably mounted on the top and rear of said receptacle, and covered by said lid when closed, a leveling device pivoted in the rear portion of said receptacle and operable from the exterior thereof, and a bucket detachably mounted in said receptacle in front of said seat, substantially as described. 115 120 125

6. A device of the character described, comprising a receptacle, a hinged lid for same, a bail and means automatically operated by the lifting of said bail for lifting said lid, lugs carried by said lid and nor- 130

5 mally engaging said bail and preventing the lifting of said lid independently of said bail, a seat piece detachably mounted on the top and rear of said receptacle, and covered by said lid when closed, a leveling device pivoted in the rear portion of said receptacle and operable from the exterior thereof, and a bucket detachably mounted in said receptacle in front of said seat, substantially as described.

10 7. A device of the character described, comprising a receptacle cut away on its front upper edge, a hinged lid for same having a downwardly projecting flange registering with said cut away portion of the receptacle, a bail and means automatically operated by the lifting of said bail for lifting said lid, a seat piece detachably mounted on the top and rear of said receptacle, and covered by said lid when closed, a leveling device pivoted in the rear portion of said receptacle and operable from the exterior thereof, and a bucket detachably mounted in said receptacle in front of said seat, substantially as described.

15 8. A device of the character described, comprising a receptacle cut away on its front upper edge, a hinged lid for same having a downwardly projecting flange registering with said cut away portion of the receptacle, a bail and means automatically operated by the lifting of said bail for lifting said lid, lugs carried by said lid and normally engaging said bail and preventing the lifting of said lid independently of said bail, a seat piece detachably mounted on the top and rear of said receptacle, and covered by said lid when closed, a leveling device pivoted in the rear portion of said receptacle and operable from the exterior thereof, substantially as described.

20 9. A device of the character described, comprising a receptacle cut away on its front upper edge, a hinged lid for same having a downwardly projecting flange registering with said cut away portion of the receptacle, a bail and means automatically operated by the lifting of said bail for lifting said lid, and a seat piece detachably mounted on the top and rear of said receptacle, and covered by said lid when closed, substantially as described.

25 10. A device of the character described, comprising a receptacle cut away on its front upper edge, a hinged lid for same having a downwardly projecting flange registering with said cut away portion of the receptacle, a bail and means automatically operated by the lifting of said bail for lifting said lid, lugs carried by said lid and normally engaging said bail and preventing the lifting of said lid independently of said bail, and a seat piece detachably mounted

30 on the top and rear of said receptacle, and covered by said lid when closed, substantially as described.

11. A device of the character described, comprising a receptacle, a hinged lid for same, a bail and means automatically operated by the lifting of said bail for lifting said lid, a seat piece detachably mounted on the top and rear of said receptacle, and covered by said lid when closed, and a leveling device pivoted in the rear portion of said receptacle and operable from the exterior thereof, substantially as described.

35 12. A device of the character described, comprising a receptacle, a hinged lid for same, a bail and means automatically operated by the lifting of said bail for lifting said lid, lugs carried by said lid and normally engaging said bail and preventing the lifting of said lid independently of said bail, a seat piece detachably mounted on the top and rear of said receptacle, and covered by said lid when closed, and a leveling device pivoted in the rear portion of said receptacle and operable from the exterior thereof, substantially as described.

40 13. A device of the character described, comprising a receptacle cut away on its front upper edge, a hinged lid for same having a downwardly projecting flange registering with said cut away portion of the receptacle, a bail and means automatically operated by the lifting of said bail for lifting said lid, a seat piece detachably mounted on the top and rear of said receptacle, and covered by said lid when closed, and a leveling device pivoted in the rear portion of said receptacle and operable from the exterior thereof, substantially as described.

45 14. A device of the character described, comprising a receptacle cut away on its front upper edge, a hinged lid for same having a downwardly projecting flange registering with said cut away portion of the receptacle, a bail and means automatically operated by the lifting of said bail for lifting said lid, lugs carried by said lid and normally engaging said bail and preventing the lifting of said lid independently of said bail, a seat piece detachably mounted on the top and rear of said receptacle, and covered by said lid when closed, and a leveling device pivoted in the rear portion of said receptacle and operable from the exterior thereof, substantially as described.

50 15. A device of the character described, comprising a receptacle cut away on its front upper edge, a hinged lid provided with a crank arm and having a downwardly projecting flange registering with said cut away portion of the receptacle, a pivoted bail provided with an arm projecting from one of its pivots, a sliding operating shaft hinged to said crank arm, and a link hinged to said operating rod and having a projecting arm

adapted to engage said arm on the bail, substantially as described.

16. A device of the character described, comprising a receptacle cut away on its front upper edge, a hinged lid provided with a crank arm for same having a downwardly projecting flange registering with said cut away portion of the receptacle, a pivoted bail provided with an arm projecting from one of its pivots, a sliding operating shaft hinged to said crank arm, a link hinged to said operating rod and having a projecting arm adapted to engage said arm on the bail, and a seat piece detachably mounted on the top and rear of said receptacle, and covered by said lid when closed, substantially as described.

17. A device of the character described, comprising a receptacle, a hinged lid therefor provided with a crank arm, a pivoted bail provided with an arm projecting from one of its pivots, a sliding operating shaft hinged to said crank arm, and a link hinged to said operating rod and having a projecting arm adapted to engage said arm on the bail, substantially as described.

18. A device of the character described, comprising a receptacle, a hinged lid therefor provided with a crank arm, a pivoted bail provided with an arm projecting from one of its pivots, a sliding operating shaft hinged to said crank arm, a link hinged to said operating rod and having a projecting arm adapted to engage said arm on the bail, and a seat piece detachably mounted on the top and rear of said receptacle, and covered by said lid when closed, substantially as described.

19. A device of the character described, comprising a receptacle, a hinged lid therefor provided with a crank arm, a pivoted bail provided with an arm projecting from one of its pivots, a sliding operating shaft hinged to said crank arm, a link hinged to said operating rod and having a projecting arm adapted to engage said arm on the bail, a seat piece mounted on the top and rear of said receptacle, and covered by said lid when closed, and a leveling device pivoted in the rear portion of said receptacle and operable from the exterior thereof, substantially as described.

20. A device of the character described, comprising a receptacle, a hinged lid therefor provided with a crank arm, a pivoted bail provided with an arm projecting from one of its pivots, a sliding operating shaft hinged to said crank arm, a link hinged to said operating rod and having a projecting arm adapted to engage said arm on the bail, a seat piece mounted on the top and rear of said receptacle, and covered by said lid when closed, a leveling device pivoted in the rear portion of said receptacle and operable from the exterior thereof, and a bucket detach-

ably mounted in said receptacle in front of said seat, substantially as described.

21. A device of the character described, comprising a receptacle, a hinged lid therefor provided with a crank arm, a pivoted bail provided with an arm projecting from one of its pivots, a sliding operating shaft hinged to said crank arm, and a link hinged to said operating rod and having a projecting arm adapted to engage said arm on the bail, with stops carried by said lid and adapted to engage said bail and prevent said lid from being lifted independent of said bail, substantially as described.

22. A device of the character described, comprising a receptacle, a hinged lid therefor provided with a crank arm, a pivoted bail provided with an arm projecting from one of its pivots, a sliding operating shaft hinged to said crank arm, a link hinged to said operating rod and having a projecting arm adapted to engage said arm on the bail, with stops carried by said lid and adapted to engage said bail and prevent said lid from being lifted independent of said bail, and a seat piece detachably mounted on the top and rear of said receptacle, and covered by said lid when closed, substantially as described.

23. A device of the character described, comprising a receptacle cut away on its front upper edge, a hinged lid for same having a downwardly projecting flange registering with said cut away portion of the receptacle, a bail and means automatically operated by the lifting of said bail for lifting said lid, with stops carried by said lid and adapted to engage said bail, and prevent said lid from being lifted independent of said bail, a seat piece detachably mounted on the top and rear of said receptacle, and covered by said lid when closed, and a leveling device pivoted in the rear portion of said receptacle and operable from the exterior thereof, substantially as described.

24. A device of the character described, comprising a receptacle cut away on its front upper edge, a hinged lid for same having a downwardly projecting flange registering with said cut away portion of the receptacle, a bail and means automatically operated by the lifting of said bail for lifting said lid, lugs carried by said lid and normally engaging said bail and preventing the lifting of said lid independently of said bail, with stops carried by said lid and adapted to engage said bail and prevent said lid from being lifted independent of said bail, a seat piece detachably mounted on the top and rear of said receptacle, and covered by said lid when closed, and a leveling device pivoted in the rear portion of said receptacle and operable from the exterior thereof, substantially as described.

HOWARD EMERSON AMES.
